GOLF PRACTICE DEVICE OR THE LIKE

Clarence Karstadt, 15920 Miami Way,
Pacific Palisades, Calif.

Filed Aug. 22, 1960, Ser. No. 61,833

Term of patent 7 years

(Cl. D34—5)

Figure 1 is a perspective view of a golf practice device or the like, showing my new design;

I claim:
The ornamental design for a golf practice device or the like, substantially as shown.
